UNITED STATES PATENT OFFICE.

THEODORE WILLARD CASE, OF AUBURN, NEW YORK, ASSIGNOR TO CASE RESEARCH LABORATORY INCORPORATED, OF AUBURN, NEW YORK, A CORPORATION OF NEW YORK.

SLOT UNIT.

Application filed May 7, 1925. Serial No. 28,620.

This invention relates to a certain new and improved apparatus for taking, printing or reproducing a film record, and is particularly designed for use in producing a film record of light variations as caused by electrical variations preferably corresponding to sound wave variations, as for instance, articulate sound waves, and the method of producing such apparatus.

In apparatus of this character for producing or reproducing a film record of light variations, it has been customary to move the film past a small printing slot in a wall disposed between the film and a source of light, and it is essential that the film move past the slot in tight contact with the wall so that only the portion of the film directly in front of the slot is exposed to the light emanating from the source.

Considerable difficulty has been experienced in producing an accurate, clear and exact film record, and also in reproducing accurately the original sound from a record due to the fact that dust, film material or foreign matter collects in the slot, more particularly is scraped off the film record as it passes by the edge of the slot, and this foreign material partially obstructs the slot which is extremely small, as for illustration, .0015 of an inch in width and .1 of an inch in length. And the result is that the film record produced is somewhat unsatisfactory because of this obstruction of the slot, and for the same reason a reproduction of even a perfect film record is unsatisfactory and the object of this invention is the production of an apparatus retaining all the advantages of present similar apparatus, but in which this disadvantage is avoided.

More especially this invention is addressed to the production of a slot-containing unit of novel construction, and adapted for use in either picture-taking or picture-reproducing apparatus, as above set forth, and to the method of producing such slot-containing unit.

Other objects and advantages relate to the details of the structure for effecting the main object of this invention, and to the particular method of producing the same, all as will more fully appear from the following description, taken in connection with the accompanying drawings, in which:

Figure 1 is a diagrammatic illustration of an apparatus for producing a film record

of light variations as produced by electrical variations corresponding to articulate sound waves or musical tones.

Figure 2 is an elevation of a portion of the slot-containing unit.

Figure 3 is a longitudinal section through the slot containing unit as illustrated in Figure 2.

Figure 4 is a vertical section through the slot-containing unit illustrated in Figure 2.

Figure 5 is a diagrammatic illustration of an apparatus for reproducing sound waves from a film record.

Figure 6 is a view similar to Figure 4 of a modified form of slot unit.

In a general way, the structure of Figure 1 is the same as that disclosed in my application Serial No. 719,098 filed June 10, 1924, and comprises a variable source of cathode rays including two spaced electrodes —2— and —3— enclosed in a bulb —1—, the electrodes being connected in circuit with a source of potential as a battery —4— and a secondary —5— of a transformer, the primary —6— of which is connected in circuit with a source of potential —7— across the filament —8— and plate —9— of a space discharge device —10—, the grid —11— of which is connected in circuit with the filament —8— and the secondary —39— of a transformer, the primary —41— of which is connected in circuit with a source of potential, as a battery —42— and a microphone —43—.

In a general way, this structure includes means for varying an electric current in accordance with sound wave variations and for amplifying such variations, and thereby effecting amplified variations in the source of light —1—, the light rays emanating from which are adapted to be printed or photographed upon the film —13— moving past the narrow slot —14— in the slot-containing unit —15—. This slot-containing unit —15— may be a portion of an enclosure for the film, or a portion of an enclosure for the lamp, and takes the place of the ordinary portion of a photographing apparatus or reproducing apparatus, which contains the usual slot past which it is quite essential that the film should move in tight relation with the walls bordering the slot.

This slot-containing unit is of novel manufacture and construction, and as here shown, consists of a sheet of transparent material as the quartz or glass sheet —16— of any

suitable shape and size. Upon one face of the glass piece —16— there is formed a layer —17— of metal preferably produced in such a way that the metal is strongly adhered to the quartz or glass. This layer of metal may perhaps preferably be evaporated upon the quartz or glass, or may be electrically deposited thereon so as to form preferably a thin coating or sheet of metal upon one side of and firmly adhered to the surface of the glass plate.

Any suitable metal may be utilized for this purpose, but I have found silver effects a satisfactory result. A very thin layer of silver is highly efficient for my purpose. In the drawings, it has been desirable to greatly exaggerate the thickness of the component parts for the purpose of clarity.

When the thin coating of metal has been produced upon the glass in any suitable manner as for instance, one of those described, a small portion of the metal is scraped off the quartz or glass so as to expose a portion of the glass plate through the metal and this may be effected in any suitable way as by a diamond point or the like, so as to produce a slot or opening through the metal of a proper length and width, a size suitable for this purpose being .0015 of an inch in width and .1 of an inch in length.

After a sharply defined slot —14— as described has been formed through the thin metal coating —17—, then the metallic layer or coating or a portion of the same and the quartz or glass disclosed through the narrow elongated slot —14— is covered with a layer —18— of transparent material substantially filling the slot, and covering the surrounding metallic surface so as to form a continuous unbroken surface. Preferably a coating of a bakelite lacquer or varnish (a condensation product of phenol and formaldehyde) is formed on the metallic layer, or a portion of the same, and across and in the slot so as to fill or partially fill the latter and form a substantially continuous even or unbroken surface which becomes extremely hard and smooth when baked.

The present preferred process consists in spraying or atomizing under pressure bakelite lacquer upon the metallic coating and the quartz exposed through the slot so as to form a thin layer —18— of lacquer and then baking the lacquer to firmly unite it to the metallic coating and form a transparent hard smooth surface.

The metal layer is preferably of such extreme thinness that any inequality in the surface conformation of the baked lacquer layer, which results from the filling of the slot —14— with the lacquer, is of inconsequential character.

It will appear from this description that the slot containing unit described consists

of a thin layer of metal having a slot of the required size therethrough, the layer being firmly supported upon one side by a transparent plate of quartz or glass which covers the slot, and with a thin layer of baked bakelite lacquer filling the slot, and extending over the adjacent surface of the metal layer to form a substantially continuous unbroken even surface past which a film may move in tight relation. Marked advantages are obtained by applying the slot filling and covering layer in liquid form as by spraying under pressure upon the metallic layer, and then reducing the same to an extreme hardness as by baking, and for these reasons bakelite lacquer is peculiarly adapted for my process and the product.

In Figure 5 the slot-containing unit —15— is constructed in the same manner as that described in connection with Figs. 1 to 4 inclusive, but for the particular use there illustrated, viz, the reproduction of talking pictures, the light from the suitable source as lamp —20— passes through the slot —14— formed in the metal layer —17— also passing through the glass or quartz member —16— and the layer —18— of baked bakelite lacquer and then passes through the film —21— which constitutes the sound record and strikes the light sensitive cell —22— which may be formed of any suitable material that varies its resistance in accordance with the intensity of the light to which it is subjected, as for instance, selenium.

The light cell —22— may, as shown, be connected in circuit with a suitable source of potential as battery —24— across the filament —25— and grid —26— of a space discharge device —27—, the filament —25— and plate —28— of which device are connected in circuit with a source of potential as battery —29—, and a translating device as the telephone receivers —30—.

For the purpose of compensating for variation in light cells as manufactured, or other varying conditions, a potentiometer —31— and a fixed resistance —32— may be placed across the filament and grid of the electron discharge device —27—.

In Figure 6 the quartz or glass member —16— is rounded or formed as a portion of a cylinder with the metallic layer on the exterior of the cylindrical surface and the bakelite lacquer layer upon the surface of the metallic layer and in the slot in the same manner as heretofore described. In forming the unit, this construction may have certain advantages due to the fact that the film will move in tight relation with the unit only at points adjacent the slot.

It will be obvious that by the method described a slot-containing unit is formed adapted to take the place of the usual slot

or the adjacent portion of any structure that incorporates such a slot, and through which the light is adapted to pass to a film in a substantially unobstructed manner, while at the same time the entry of foreign matter to the slot is prevented either by the scraping of the film across the edge of the slot as in the usual structure, or otherwise, and altho I have shown and described a specific structure as illustrative of an embodiment of my invention which is at present perhaps preferred, I do not desire to restrict myself to the details of the structure or the particular materials from which the same is formed, or to the exact form and relation of the parts, as various changes may be made within the scope of the appended claims.

I claim:

1. In an apparatus of the character described, a transparent member, an opaque member in contact with the transparent member and having a slot therethrough, and a transparent lacquer filling the slot and covering the adjacent surface of the opaque member.
2. In an apparatus of the character described, a transparent member, an opaque member in contact with the transparent member and secured thereto and having a slot therethrough, and a hard smooth baked transparent lacquer filling the slot.
3. In an apparatus of the character described, a transparent member, an opaque member in contact with the transparent member and having a slot therethrough, and a transparent condensation product of phenol and formaldehyde filling the slot and covering the adjacent surface of the opaque member.
4. In an apparatus of the character described, a glass member, a thin metallic layer secured to the glass member and having a slot extending through the layer, and a transparent lacquer filling the slot and covering the adjacent surface of the metallic layer.
5. In an apparatus of the character described, a glass member, a thin metallic layer secured to the glass member and having a slot extending through the layer, and a hard smooth baked transparent lacquer filling the slot and covering the adjacent surface of the metallic layer.
6. In an apparatus of the character described, a glass member, a thin metallic layer

secured to the glass member and having a slot extending through the layer, and a transparent condensation product of phenol and formaldehyde filling the slot and covering the adjacent surface of the metallic layer.

7. The method of producing a slot unit comprising forming a layer of an opaque material upon a transparent background with a narrow elongated slot through the opaque layer to expose the transparent background, then applying a transparent lacquer to the opaque layer and the transparent background exposed through the slot, and baking the lacquer.

8. The method of producing a slot unit comprising forming a layer of an opaque material upon a transparent background with a narrow elongated slot through the opaque layer to expose the transparent background, and then applying a liquid capable of becoming hard and transparent to the surface of the opaque material and the transparent background exposed through the slot.

9. The method of producing a slot unit comprising forming a layer of an opaque material upon a transparent background with a narrow elongated slot through the opaque layer to expose the transparent background, and then atomizing a liquid upon the surface of the opaque material and the transparent background exposed through the slot.

10. The method of producing a slot unit comprising forming a layer of an opaque material upon a transparent background with a narrow elongated slot through the opaque layer to expose the transparent background, and then applying bakelite lacquer to the transparent background exposed through the slot and the adjacent portions of the opaque material.

11. The method of producing a slot unit comprising forming a layer of an opaque material upon a transparent background with a narrow elongated slot through the opaque layer to expose the transparent background, and then atomizing a bakelite lacquer upon the surface of the opaque material and the transparent background exposed through the slot.

In witness whereof I have hereunto set my hand this 30th day of April 1925.

THEODORE WILLARD CASE.
